MYRON H. RICHARDSON AND ALFRED D. ANTOINE, OF CHICAGO, ILLINOIS, ASSIGNORS
TO ADVANCE MACHINE COMPANY, OF CHICAGO, ILLINOIS, A CORPORATION OF
ILLINOIS.

VENDING MACHINE.

Application filed June 23, 1924. Serial No. 721,661.

This invention relates to improvements in vending machines of the check controlled type, and one of the objects of the invention is to provide an improved machine of this character having means for locking the mechanism against operation after the last article has been delivered from the machine, and at the same time the check will be held against being deposited in the machine and will be returned to the operator.

A further object is to provide improved means for preventing the operation of the machine by means of a check or token of an improper weight and also the operation of the machine by a check or token of an improper thickness.

A further object is to provide in a machine of this character improved means for insuring the proper delivery of articles which are of a very thin construction.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which—

Figure 1 is a vertical, longitudinal, sectional view of a machine of this character constructed in accordance with the principles of this invention with parts omitted therefrom for the sake of clearness.

Figure 2 is a top plan view of the ejecting mechanism.

Figure 3 is a rear elevation of the check controlled mechanism with parts omitted.

Figure 4 is a view in elevation of the check carrier showing the means for restraining an improper check against delivery from the check carrier.

Figure 5 is a detail view of the ratchet disc operating dog and the retaining pawl for the disc, showing the parts in their normal positions.

Figure 6 is a view similar to Figure 4, showing the means for holding a check of improper weight against delivery from the check carrier.

Figure 7 is a detail sectional view as taken on line 7—7, Figure 6.

Figure 8 is a view partly in elevation and partly in section of a modified form of the

ejecting means, and showing the parts in the position they will assume when the machine is empty.

Figure 9 is a view similar to Figure 8 showing the position the parts will assume when a thin article is being ejected.

Figure 10 is a detail, rear elevation of Figure 8.

Figure 11 is a detail view partly in elevation and partly in section of the check receiving support and the co-operating check controlled element as constructed to prevent the insertion and operation of the mechanism by two thin checks.

Figure 12 is a detail plan view of the controlling gate or member between the article containers or hoppers.

Referring more particularly to the drawings the numeral 15 designates a case or cabinet having a delivery outlet 16 through which the articles to be vended are delivered. The 75 cabinet 15 is preferably provided with two holders 17 and 18 for the articles and these holders are preferably in the form of guides or hoppers separated from each other but

which have communication at their lower extremities. One of these hoppers or containers is arranged in advance of the other so that two columns of articles may be held within the machine. The articles are first delivered from the container 18 in a manner to be hereinafter set forth, and fall upon an inclined bottom 19 of the case 15 and when all of the articles have been delivered from the forward container they will be supplied from the rear container. To that end there is provided a 85 swinging gate or member 20 which is arranged beneath the open end of the container 17. This gate or member 20 swings about a suitable pivot 21 and is adapted to be moved so as to pass beneath the articles in the container 17 and support them to prevent them

from being delivered from the machine and into the position shown in dotted lines in Figure 1, to prevent them from being delivered upon the operation of the ejecting means and when the forward container holds articles to be delivered. After one article has been delivered the member 20 is moved from the dotted line position to the full line position so as to direct the articles from the rear container to a position to be ejected.

The ejecting mechanism consists of an ejector proper 22 which is slidable upon a suitable

support 23, the ejector being preferably supported by means of members 24 shaped to engage over the lateral edges of the support 23. Connected with the ejector 22 is a frame 5 like structure 25 into which the articles from the container 18 fall when the ejector 22 is retracted so that upon the release of the article from the container 18, it will fall into the frame like structure 25 which will have 10 moved directly below the container, so that the article will rest upon the support 23. When the ejector 22 is moved in a direction to deliver the article, the article will be engaged by the ejector and will fall from the 15 frame like structure or portion 25 to be delivered through the outlet 16. The frame like structure 25 also serves as a means for holding the article upon the support 23, especially when cylindrical or round articles are 20 delivered, as the walls of the frame like structure will prevent the article from rolling.

The member 20 is moved about its pivot through the medium of the ejector 22 and to that end there may be provided spaced projections 26-27 between which an arm 28, connected with the member 20 and standing adjacent one of the walls of the frame like member 25, passes. It will therefore be seen that by a reciprocating movement of the 30 ejector 22 the member 20 will be moved about its pivot, and having been raised to the dotted line position shown in Figure 1, the weight of the articles will be overcome by reason of the arm 28 on the member 20 engaging the 35 stop 26 when the plunger is advanced.

Any suitable means may be provided for reciprocating the plunger such as a pivotally mounted member 29, which is pivotally supported preferably intermediate its ends 40 by means of the pivots 30, and one end thereof is connected with the ejector 22 in any desired or suitable manner preferably by means of the bifurcated extremities 31 of the member 29 passing over projections 32 connected 45 with the ejector 22, preferably to the members 24, which in turn are connected with the ejector. The member 29 is adapted to be moved about its pivot by means of a suitable cam shaped device 33 which is adapted to be 50 rotated in a manner to be hereinafter described, and during its rotation the cam shaped portion 34 thereof will successively engage lugs or projections 35-36 carried by the member 29. When the cam 33 is rotated 55 and assuming the parts to be in the position shown in Figure 1, the cam surface 34 will engage the projection 35 and will swing the member 29 about its pivot in one direction to retract the ejector 22. When the cam surface 34 engages the projection 36 it will move the member 29 in the opposite direction so as to actuate the ejector 22 to deliver the article, it being understood that the projections 35 and 36 are arranged on opposite sides of the 60 pivot of the member 29.

The cam 33 is adapted to be actuated by check controlled mechanism preferably of the type and construction as is disclosed in United States Patent to Alfred D. Antoine, Number 1,452,721, issued April 24, 1923, and 70 which check controlled mechanism embodies a check carrier 37 having a check seat 38 therein. The check carrier is adapted to be actuated by means of a suitable handle 39 located on the outside of the case 15, and the carrier 37 is adapted to be rotated when a proper check is inserted in the mechanism, until the carrier has assumed the position shown in Figure 4, at which time and under normal conditions the check 40 is adapted 80 to be delivered from the check carrier upon a support 41. When the check rests upon the support 41 it engages a locking or retaining element 42 of the check controlled mechanism so that when the check carrier 37 is reversed in its direction of rotation, a portion of the wall of the check seat 38 will engage the edge of the check 40 to force the check from the support 41 and against the element 42 to swing the latter about its pivot 43 90 against the stress of a spring 44, thereby moving the portion 45 of the element 42 into a position that it will be rendered inactive with respect to the ratchet disc 46 to release the latter and thereby permit of the further operation of the check carrier 37 and with it the cam 33. The cam 33 is connected with the disc 46 in any suitable manner such as by means of an angular projection 47 on the cam 33, which is adapted to enter a correspondingly shaped recess 48 in the disc 46. This portion of the check controlled mechanism, aside from the cam 33, constitutes no part of the present invention, as it is fully disclosed 100 in the patent heretofore referred to.

It sometimes happens that it is attempted to actuate the mechanism when the machine is empty and in that event the check deposited by the operator would be retained in the machine at a loss to the operator.

In the present invention means are provided whereby the mechanism will be automatically locked against operation after the machine has become empty and this is preferably accomplished through the medium of the articles themselves. The check will then be returned.

A simple and efficient means for accomplishing this end includes a member 49 which is pivotally mounted as at 50 upon a suitable support. Connected with the member 49 preferably one end thereof, as at 51, remote from the pivot 50 is a rock shaft or bar 52. One end 53 of this bar or member 52 is shaped to extend into the path of movement of the articles from the container 18 to the support 23. A spring 54 may be provided for shifting the member 49 in a direction to cause the portion 53 of the member 52 to be elevated above the support 23 so that when 130

the ejector 22 is retracted, the articles in their passage to the support 23, will fall upon the portion 53 of the member 52 and actuate the latter to swing the member 49 about its pivot 50 and against the stress of the spring 54. The member 49 is provided with a finger or extension 55 which is adapted, in the normal position of the member 49, to assume a position adjacent the path of movement of the periphery of the check 40 while the latter is being carried by the check carrier, or into the position shown in Figure 4. In this position it will be manifest that when the check carrier is rotated or oscillated and when the check seat 38 is in a position to discharge or deliver the check therefrom, the check will be held against such discharge by reason of the fact that it will be engaged by the finger or projection 55 of the member 49. If, however, this finger or projection 55 is retracted the check 40 will fall from the seat 38 upon the support 41. The retraction of the finger or projection 55 is controlled, as before stated, by the articles in the container. It will therefore be manifest that when the container contains one or more articles to be delivered, the weight of the article when it passes to the support 23 upon the portion 53 of the member 52 will, as before stated, swing the member 49 about its pivot against the stress of the spring 54 to retract the member 55.

When the container is empty, no weight will be applied to the portion 53 of the member 52, with the result that the finger or extension 55 will be advanced or projected by the movement of the member 49 about its pivot 50 under the influence of the spring 54. Obviously the ejector 22 is so shaped that the reciprocation thereof will not be interfered with by the portion 53 of the member 52.

The wall of the casing of the housing in which the check carrier 37 is located may be provided with a suitable aperture or opening 56 (see Figures 1 and 3), through which the finger or extension 55 is adapted to project.

It sometimes happens that it is attempted to actuate the mechanism through the medium of a check or token of an improper weight, even though the articles to be delivered are held within the container and the finger or projection 55 is retracted. In order to prevent such improper check (such as a fibre or non-metallic disc) from being delivered into the mechanism so that the latter might be operated thereby, a suitable detector is provided therefor and which, as shown more clearly in Figures 6 and 7, consists of a spring like member 57 preferably in the form of a leaf spring anchored as at 58 to a suitable support. The end of the spring 57 is shaped as at 59 and stands in close proximity to the face of the check carrier 37. The normal tendency of the portion 59 of the spring 57 is to enter the check seat 38, from the side

thereof, when the check carrier is rotated. The stress of the spring 57 is such that a proper check or token will not be held against delivery from the seat 38 at the proper point in the operation of the check carrier, owing to the weight of the check or token, the stress of the spring 57 being such that it will readily yield under the proper weight of check. If, however, the check 60 is of an improper weight the portion 59 of the spring 57 will, when the check 60 is moved adjacent thereto, engage the lateral face of the check and hold the same against discharge from the seat 38 so that when the check carrier 37 is moved in the opposite direction the check 60 will be returned to the check receiving opening 61 to be returned to the operator. The portion 59 of the spring 57 is so shaped that in the event of the rotation of the check carrier 37 when no check is present in the seat 38, it will not interfere with the rotation of the check carrier, that is to say the spring 57 will not engage the wall of the check seat 38 in a manner that will prevent the rotation of the check carrier 37.

Any suitable means may be provided for varying the stress of the spring 57. A suitable and efficient means embodies an adjustable member such as a screw or bolt 62 (see also Figure 2) which is adjustably mounted upon any suitable support 63 and engages the spring 57, so that by adjusting the screw or bolt 62 the spring 57 may be caused to exert a greater or less stress upon the check 60. If desired a lock nut or collar 64 may be provided for maintaining the screw or bolt 62 in its adjusted position.

It is thought that the operation of this portion of the mechanism will be clearly understood from the foregoing but briefly stated it is as follows. When a check is inserted in the check receiving opening 61, and assuming the parts to be in the position shown in Figures 1 and 2, and assuming that the containers 17 and 18 hold articles to be delivered, the operator by rotating the handle 39 will cause the check 40 to be advanced to the position shown in Figure 4, and at the same time the cam 33 will be rotated to retract the ejector 22 from the position shown in Figure 1, so as to permit one of the articles to be delivered to the support 23 through the frame like portion 25 of the ejector. At the time that the ejector is being retracted the gate or member 20 will be swung about its pivot from the full line position to the dotted line position to prevent articles in the container 17 from being delivered therefrom. As soon as the ejector 22 is retracted from the position shown in Figure 1, one of the articles will fall upon the portion 53 of the member 52 to swing the member 49 about its pivot 50 and thereby retract the finger 55. This will permit the check 40 to be delivered from the check carrier 37 upon the support 41 and into engage-

ment with the element 42 of the check controlled mechanism. When the check carrier 37 is reversed in its direction of movement one of the walls of the seat 38 will force the check between the support 41 and the element 42 to release the ratchet disc 46 and thereby permit of the operation of the ejector. At the same time the check will fall from the support 42 through a suitable opening 65 (see Figure 1) into a check receiving receptacle 66, which latter is removably secured in any suitable manner within the case 15. During this movement the article will be ejected from the support 23 by the forward movement of the ejector 22 or by its movement into the position shown in Figure 1.

In the event that there is no article in either of the containers 17 and 18, the finger 55 will not be retracted but will assume the position shown in Figure 4 and will prevent the check 40 from being delivered from the check carrier 37.

When it is desired to dispense articles which are very thin and flat, there is provided a suitable member 67, which is secured beneath the support 23 adjacent the delivery end of the latter. The ends of this member 67 are shaped to extend around the lateral edges of the support 23 and above the support. The ends 68 of the members 67 are deflected downwardly towards the support 23 and terminate short thereof to form a space 69 and which space is of a size only slightly greater than the thickness of the article 70 to be dispensed. These extremities 68 are preferably located in close proximity to the lateral edges of the support 23 and at points where they will engage the extremities of the articles 70 being vended. If desired suitable filler members 71 (see Figures 8 and 10) may be provided between the lower face of the support 23 and the member 67 so as to permit of an adjustment of the portions 68 to move the extremities farther away from or closer to the face of the support 23 to vary the size of the spaces therebetween and thereby compensate the varying thicknesses of articles to be vended.

In this form of the invention and as shown in Figures 8, 9, and 10, the ejector 72 is actuated in the same manner as in the form of the invention heretofore described and through the medium of the oscillation of the pivotally mounted member 29. The ejector, however, preferably consists of a substantially thin plate which is of a thickness slightly less than the space 69 between the ends 68 of the member 67 and the face of the support 23 so that when the ejector 72 is projected, as shown more clearly in Figure 9, it will engage the edge of the article 70 to eject the latter.

As a means for guiding the ejector and for holding the parts in the proper position there may be provided another filler member 73,

which may be secured to any fixed portion of the mechanism. The end 74 of the member 73 (see particularly Figures 8 and 9) is deflected as shown and the lower face of the deflected portion is arranged in close proximity to the upper surface of the ejector 72 to rest thereagainst.

The articles 70 to be vended are contained within a suitable hopper or container 75 and in order to exert the necessary weight upon the articles so as to cause them to be advanced in the container 75, a suitable weight 76 may be provided. This weight is provided with a suitable opening 77 therein to receive the end or portion 53 of the member 52 and thereby prevent the retraction of the finger or projection 55 on the member 49 by the weight 76 when there are no articles in the container 75.

The operation of this form of the invention is the same as that described in connection with the form of the invention shown in Figures 1 and 2.

As a means for preventing the operation of the mechanism by the insertion of two checks which are not in themselves of the required size or denomination and which when placed side by side would produce a formation of the required width and possibly of the required weight of a proper check suitable provision is made for displacing one of these checks with respect to the other so that they will fall into the machine when inserted and the mechanism will not be actuated thereby. To that end (reference being had more particularly to Figures 4 and 11) the face of the support 41 upon which the check is received from the check seat 38, is reduced or cut away as at 78 leaving a very narrow surface 79 to be engaged by the edge of the check. The adjacent face of the element 42 of the check controlled mechanism is also provided with a cut away or recessed portion 80 and is shaped to form a check engaging surface 81. In the event that a check of the proper width or denomination is inserted and is delivered from the check seat 38 upon the surface 79 of the support 41, it will be manifest that the check will be properly supported and will be prevented from entering the reduced portion 78 and at the same time the check will span the opening 80 in the check controlled element 42 and the mechanism will be operated but, as shown in Figure 11, when two thin checks are simultaneously inserted and delivered from the check seat a portion of one of the thin checks 82 will enter the cut away or reduced portion 78 of the support 41 and a portion of the other check 82 will enter the cut away or recessed portion 80 of the element 42 and it will be manifest that they will drop through the mechanism without actuating the latter.

If desired the gate or member 20 may be provided with a projecting portion or extension 20^a which when the member 20 is moved into the position shown in dotted lines in Fig-

ture 1, will prevent the articles or packages 17 from becoming wedged and will assist in supporting them.

Furthermore as the member 20 is moved from the position shown in dotted lines in Figure 1, to the full line position, the extension or portion 20^a will engage and assist in ejecting the article 18 from the rear to the front compartment or container. This action is rendered possible because the member 20 will be positively moved about its pivot through the medium of the arm 28 being engaged by the lug 27.

While the preferred forms of the invention have been herein shown and described it is to be understood that various changes may be made in the details of construction and in the combination and arrangement of the several parts, within the scope of the claims, without departing from the spirit of this invention.

What is claimed as new is:—

1. A vending machine including a container for the articles to be vended, an ejector for the articles, check controlled means for actuating the ejector, and means controlled by the articles in the said container for rendering the ejector inoperative by the check controlled means, the second recited means embodying an element adapted to be positioned in the path of movement of the check from the check seat in the check carrier for maintaining the check against delivery from the check carrier.

2. A vending machine including a container for the articles to be vended, an ejector for the articles, check controlled mechanism for actuating the ejector, said mechanism including a forwardly and backwardly movable check carrier and with respect to which carrier the check is shiftable to actuate the ejector, and means directly controlled by the articles to be vended for rendering the ejector inoperative with respect to the actuating mechanism therefor, the last recited means including mechanism for restraining the check against shifting movement with respect to the said check carrier.

3. A vending machine including a container for the articles to be vended, an ejector for the articles, check controlled mechanism for actuating the ejector, said mechanism including a forwardly and backwardly movable check carrier and with respect to which carrier the check is shiftable to actuate the ejector, and means directly controlled by the articles to be vended for rendering the ejector inoperative with respect to the actuating mechanism therefor, the last recited means including an element operable to engage and hold the check upon its seat upon the check carrier and in a position that the ejector actuating mechanism will remain inactive.

4. A vending machine including a container for the articles to be vended, an ejector for ejecting them, actuating mechanism

for the ejector, a forwardly and backwardly movable check carrier having a check seat, said check being delivered from the said seat at a predetermined point in the operation of the check carrier, the said mechanism including means operable by the check when delivered from said seat to render the said mechanism active, and means controlled by the articles in the container for maintaining the check upon its seat in the carrier to render the said actuating mechanism inactive.

5. A vending machine including a container for the articles to be vended, an ejector for ejecting them, actuating mechanism for the ejector, a forwardly and backwardly movable check carrier having a check seat, said check being delivered from the said seat at a predetermined point in the operation of the check carrier, the said mechanism including means operable by the check when delivered from said seat to render the said mechanism active, and a finger controlled by the articles in the container for engaging the periphery of the check to retain the check upon its seat in the said carrier.

6. A vending machine including a container for the articles to be vended, ejecting means for the articles, a forwardly and backwardly movable check carrier having a check seat, said check being delivered from the said seat at a predetermined point in the operation of the check carrier, said ejecting means including mechanism for rendering the same active when the check is unseated, and means controlled by the articles to be vended for retaining the check upon its seat.

7. A vending machine including a container for the articles to be vended, ejecting means for the articles, a forwardly and backwardly movable check carrier having a check seat, said check being delivered from the said seat at a predetermined point in the operation of the check carrier, said ejecting means including mechanism for rendering the same active when the check is unseated, an element for retaining the check upon its seat, means tending normally to render the said element active, and means whereby the said element will be rendered inactive to permit the check to be unseated when the said container contains one of the articles to be vended.

8. A vending machine including a container for articles to be vended, an ejector for the articles, check controlled mechanism including a check carrier having an open check seat therein, means for actuating the carrier to invert the said seat to deliver the check therefrom, means for actuating the ejector when the check is delivered from the check carrier, and means adapted to engage the edge of the check in the seat for holding the check against delivery from the seat under predetermined conditions.

9. Check controlled mechanism including a

check carrier having an open check seat therein, means for actuating the carrier to invert the said seat to deliver the check therefrom, means adapted to engage the side face of the check in the seat for holding the check against delivery from the seat under predetermined conditions, and means for varying the stress of the last recited means.

10. A vending machine including a container for articles to be vended, means for releasing the articles, check controlled mechanism including a check carrier having an open seat therein, means for actuating the carrier to invert the seat to deliver the check therefrom, means for actuating the said releasing means when the check is delivered from the check carrier, an element movable to a position adjacent the path of movement of the check to retain the latter in the said seat under predetermined conditions, and means operatively connected with the said element and positioned to be engaged by the articles in the container whereby the said element will be rendered inactive to permit 25 the check to be delivered from the check seat.

11. A vending machine including a container for articles to be vended, means for releasing the articles, check controlled mechanism including a check carrier having an open seat therein, means for actuating the carrier to invert the seat to deliver the check therefrom, means for actuating the said releasing means when the check is delivered from the check carrier, an element movable to a position adjacent the path of movement of the check in the carrier to engage the edge of the check to retain the latter in the said seat under predetermined conditions, and means embodying a finger adapted to be po-

sitioned by the articles in the container to engage the edge of the check for holding the check in the said seat to prevent its delivery from the seat when the latter is inverted.

12. A vending machine including a container for the articles to be vended, means for delivering the articles from the container, check controlled means for controlling the first said means, said check controlled means embodying a check carrier having an open check seat, means for actuating the carrier to discharge the check from said seat, and means controlled by the articles in the container for rendering the article delivery means inactive, the last recited means embodying an element movable by the articles in the container to a position to form an obstruction to prevent discharge of the check from said seat.

13. A vending machine including a container for the articles to be vended, means for delivering the articles from the container, check controlled means for controlling the first said means and embodying a check carrier having an open seat for the check, means for actuating the check carrier whereby the check will be delivered therefrom, and means controlled by the articles in the container for rendering the article delivery means inactive, the last recited means embodying an element adapted to be positioned to form a closure for the check seat to maintain the check against delivery from the check carrier.

In testimony whereof we have signed our names to this specification, on this 20th day of June, A. D. 1924.

MYRON H. RICHARDSON.
ALFRED D. ANTOINE.
